A. A. BACKHAUS,
APPARATUS FOR THE PRODUCTION OF HALOGENATED HYDROCARBONS,
APPLICATION FILED MAY 7, 1919.

1,402,338.

Patented Jan. 3, 1922.

UNITED STATES PATENT OFFICE.

ARTHUR A. BACKHAUS, OF BALTIMORE, MARYLAND, ASSIGNOR TO U. S. INDUSTRIAL ALCOHOL CO., A CORPORATION OF WEST VIRGINIA.

APPARATUS FOR THE PRODUCTION OF HALOGENATED HYDROCARBONS.

1,402,338.

Specification of Letters Patent.

Patented Jan. 3, 1922.

Application filed May 7, 1919. Serial No. 295,474.

To all whom it may concern:

Be it known that I, ARTHUR A. BACKHAUS, a citizen of the United States, residing at Baltimore, in the State of Maryland, 5 have invented a certain new and useful Improvement in Apparatus for the Production of Halogenated Hydrocarbons, of which the following is a specification.

My invention relates particularly to an 10 apparatus for producing halogenated hydrocarbons, but has reference especially to the production of ethylene dichloride.

The object of my invention is to provide an apparatus by means of which unsaturated hydrocarbons may be halogenated, and especially by means of which ethylene dichloride may be made from ethylene in an advantageous manner and with a high yield. Further objects of my invention are 20 to provide an apparatus of the above character which is operated with the exclusion of light, the maintenance of an excess of the unsaturated hydrocarbon, such for example as ethylene, throughout the treatment, and the maintenance of a comparatively low temperature during the treatment.

Further objects of my invention will appear from the detailed description thereof 30 set forth hereinafter.

While my invention is capable of being carried out in many different ways, for the purpose of illustration I have shown only one type of apparatus made in accordance 35 with my invention in the accompanying drawings, in which:

The figure is a diagrammatic representation partly in section of an apparatus made in accordance with my invention.

40 Assuming that the apparatus is to be used for the treatment of ethylene with chlorine to produce ethylene dichloride, ethylene gas is conveyed by means such as a pipe 1 into a chamber 2. In the embodiment shown this is formed by a cover plate 3, which is shown as secured to a cylindrical casing 4, in such a manner as to hold between the cover plate 3 and the cylinder 4 a perforated plate 5, carrying in the same 45 the ends of a series of tubes 6. These are shown as held in place in a similar manner at their lower ends by means of a perforated plate 7, located between the cylinder 4 and a bottom plate 8, which form a cham-

ber 9 at the lower end of the apparatus. 55 The cylinder 4 is preferably kept cool by means such as a counter-current of water which may be admitted by a pipe 10, and which flows out of the cylinder 4 by means such as a pipe 11. Chlorine gas is preferably admitted to the chamber 2 by means such as a pipe 12 in the proportion of ten volumes of chlorine to eleven volumes of ethylene, these proportions being chosen so as to maintain at all times throughout the 65 treatment an excess of ethylene present. In the embodiment shown the chlorine and ethylene after entering the chamber 2 pass downwardly through the tubes 6, where they become united to form ethylene dichloride, the temperature being kept low at all times by means of a current of water in the cylinder 4. The ethylene dichloride, together with some chlorine dissolved therein, and some gaseous ethylene, pass out of the 70 chamber 9 by means of a pipe 13 and into a receiver 14, where the pipe 13 terminates as near the bottom of the receiver as possible, so as to form a liquid seal within the receiver. The liquid within the receiver 75 14 will at first be comprised of ethylene dichloride having chlorine dissolved therein. As the process continues to be carried out, the gaseous ethylene which descends in the pipe 13 will be bubbled through the liquid 80 in the receiver 14, so as to combine with all the chlorine which is dissolved in the liquid, so that in this manner ethylene dichloride entirely free from any uncombined chlorine is obtained, and may be drawn off 85 90 from time to time through a valved pipe 15 in the bottom of the receiver. The excess of the ethylene passes out of the receiver 14 by means such as a pipe 16, which preferably conducts the ethylene back to 95 the chamber 2, where the ethylene is thus again brought into contact with chlorine, so as to form ethylene dichloride in the same manner as previously described.

It will be understood that all of the apparatus above described is ordinarily made of an opaque material of such a character as not to be acted upon by the substances present, and may for example be made throughout of iron. The temperature is 100 kept as low as possible, and in any event as low as 50° C., as indicated by the temperature in the materials flowing out of

the chamber 9. By excluding the light and keeping the temperature as low as possible, very high yields are obtained, that is to say 96 and 97% of the ethylene treated is 5 changed to ethylene dichloride, inasmuch as in this manner substitution of hydrogen atoms by the halogen used is obviated. Furthermore, it will be understood that instead of ethylene other unsaturated hydro- 10 carbons may be used, as for example butylene or amylene, and that, instead of the chlorine the other halogens may be used.

The word "pipes" in the claims is intended to refer to any form of conduit for 15 conveying liquids or gases from one place to another.

While I have described my invention above in detail, I wish it to be understood that many changes may be made therein 20 without departing from the spirit thereof.

I claim:

1. A chlorinating apparatus comprising a container containing pipes and means for cooling them, means for introducing chlorine 25 and a gas at one end of the pipes, a conduit leading from the other end of the pipes to the bottom of a receptacle, and a pipe connecting the latter with the means for introducing chlorine and the gas.
2. A chlorinating apparatus comprising 30 a container containing vertical pipes and means for cooling them, means for introducing chlorine and a gas at the top of the pipes, a conduit leading from the other end of the

pipes to the bottom of a receptacle, and a 35 pipe connecting the latter with the means for introducing chlorine and the gas.

3. A chlorinating apparatus comprising a container having chambers at each end, pipes connecting said chambers, means for cooling 40 the container and the pipes, an inlet for chlorine and a gas to the upper chamber, an outlet for the lower chamber leading to a receptacle, and a pipe connecting the receptacle to the upper chamber.

4. A chlorinating apparatus comprising a long vertical container having chambers at each end, pipes connecting said chambers, means for cooling the container and the pipes, an inlet for chlorine at the top of the 50 upper chamber and an inlet for gas at the side thereof, an outlet at the bottom of the lower chamber leading to the bottom of a receptacle, and a pipe connecting the top of the receptacle to the upper chamber.

5. A halogenating apparatus comprising a reaction chamber, a receiver for the liquid halogenated product, means for bubbling gaseous materials from the reaction chamber through the liquid in the receiver, means for 60 returning any unhalogenated gas to the reaction chamber, and means for cooling the reaction chamber.

In testimony that I claim the foregoing, I have hereunto set my hand this 22nd day 65 of April, 1919.

ARTHUR A. BACKHAUS.
